(57) **CLAIM**

We claim the ornamental design for an ultrasonic treatment device, as shown and described.

DESCRIPTION

FIG. 1 is a front corner perspective view of an ultrasonic treatment device according to an embodiment of the invention.

FIG. 2 is a top plan view of the ultrasonic treatment device according to an embodiment of the invention.

FIG. 3 is a bottom view of the ultrasonic treatment device according to an embodiment of the invention.

FIG. 4 is a front elevational view of the ultrasonic treatment device according to an embodiment of the invention.

FIG. 5 is a rear elevational view of the ultrasonic treatment device according to an embodiment of the invention.

FIG. 6 is a right side elevational view of the ultrasonic treatment device according to an embodiment of the invention.

FIG. 7 is a left side elevational view of the ultrasonic treatment device according to an embodiment of the invention; and,

FIG. 8 is a front corner perspective view of the ultrasonic treatment device in a stored configuration according to an embodiment of the invention.

In the drawings, the broken lines depict unclaimed subject matter only and form no part of the claimed design.
